Patented Jan. 8, 1918.

UNITED STATES PATENT OFFICE.

JOHN W. COX, OF ERIE, PENNSYLVANIA.

TRUCK-PLATFORM.

1,252,786.

Specification of Letters Patent. Patented Jan. 8, 1918.

Application filed April 26, 1917. Serial No. 164,777.

To all whom it may concern:

Be it known that I, JOHN W. COX, a subject of the King of Great Britain, having declared my intention of becoming a citizen 5 of the United States, residing at Erie, in the county of Erie and State of Pennsylvania, have invented new and useful Improvements in Truck-Platforms, of which the following is a specification.

10 This invention relates to truck platforms and consists in certain improvements in the construction thereof as will be hereinafter fully described and pointed out in the claims.

15 Truck platforms are used in connection with loads which are to be lifted by an elevating platform truck. These carry heavy loads and, therefore, must be of rigid construction. At the same time the supports 20 should take as little room as possible especially along one direction so as to permit the ready entry of the elevating truck under the platform.

The invention is illustrated in the accompanying drawings as follows:—

25 Figure 1 shows an end elevation, partly in section.

Fig. 2 a side elevation partly in section.

Fig. 3 a top view showing the corner 30 construction.

Fig. 4 an end view of one of the legs.

Fig. 5 a side view of one of the legs.

35 Fig. 6 an opposite view of one of the legs from that shown in Fig. 5.

Fig. 1 marks the legs. These are substantially flat in one direction and are provided with the faces 2 to which the side bars 3 are attached. These are preferably in the form of channel bars and are secured by means of 40 the rivets 4, a shoulder 5 cast on the leg extending along the bottom edge of the bar making the connection more secure.

The legs have the lateral projections 6 on which the end bars 7 are secured. The 45 end bars are in the form of channels and the projections 6 are arranged in the channels, the bars being secured to the projections by means of rivets 8. This makes a very rigid frame and leaves the space between the legs at the ends practically unobstructed.

The floor 9 of the platform is flush with the surface of the bar 7. The bar 7 forming the edges of the floor takes the wear at this

point. The floor is secured to the bars 3 by means of the bolts 10.

A box is provided for the platform having the ends 11 and sides 12. An angle iron 13 extends around the corner. Bolts 14 extend through the angle iron and the sides 12. 60 A bolt 15 extends through the angle iron and top board of the end.

It will be noted that the end boards extend past the side boards and are thus locked in the angle. Posts 16 are arranged in the corners. These posts have the feet 17 which extend along the channel 7 and the bolts 17^a extend through these feet, channel bars and the projections 8 of the legs thus firmly securing the posts. The bolts 14 not only extend through the angle iron 13 and the ends 12 but also through the posts 16. Tie rods 18 extend from angle iron to angle iron, the tie rods being arranged in spaces 19 between the boards forming the sides and ends of the box. The box may be readily moved by simply loosening the bolts 17^a. The angle irons 13 extend around the ends of the channel 7, thus locking the box in place on the platform.

80 What I claim as new is:—

1. In a truck platform, the combination of legs having lateral projections at their top; frame bars secured to the sides of the legs extending at right angles to the projections connecting the legs at the sides of the platform; channel bars secured to the projections and connecting the legs at the ends of the platform, the projections being arranged in the channel; and a floor flush with 85 the channel bars and secured to the side bars.

2. In a truck platform, the combination of legs; bars connecting the legs at the sides and ends; and a box formed with side 95 planks and corner angle irons, the angle irons at the corners projecting below the planks and interlocking with the frame formed by the legs and bars.

3. In a truck platform, the combination 100 of legs; bars connecting the legs and forming a frame; a floor on the frame; and a box having planks with angle irons at the corners, the angle irons extending below the planks and around the floor of the platform 105 for securing the box in place on the platform.

4. In a truck platform, the combination

of a frame formed of legs and connecting bars; box posts at the corners, said box posts consisting of uprights and laterally projecting feet; means for securing the feet to the frame; planks forming the sides of the box; angle irons arranged at the corners; and bolts extending through the posts, planks and angle irons.

5. In a truck platform, the combination 10 of a frame formed of legs and connecting bars; box posts at the corners, said box posts consisting of uprights and laterally projecting feet; means for securing the feet to the frame; planks forming the sides of 15 the box; angle irons arranged at the corners;

bolts extending through the posts, planks and angle irons; and tie rods connecting the angle irons.

6. In a truck platform, the combination of legs; bars connecting the legs at the sides 20 and ends; a box formed with side planks and corner angle irons, the angle irons at the corners projecting below the planks and interlocking with the frame formed by the legs and bars; and tie rods connecting the 25 angle irons.

In testimony whereof I have hereunto set my hand.

JOHN W. COX.
